UNITED STATES PATENT OFFICE.

MARSHALL FRANKLIN DIAL, OF KEDRON, ARKANSAS.

BACK-BAND HOOK.

SPECIFICATION forming part of Letters Patent No. 600,412, dated March 8, 1898.

Application filed June 1, 1896. Serial No. 593,955. (No model.)

To all whom it may concern:

Be it known that I, MARSHALL FRANKLIN DIAL, of Kedron, Cleveland county, Arkansas, have invented a new and useful Improvement 5 in Back-Band Hooks, which improvement is fully set forth in the following specification.

The invention relates to improvements in back-band hooks.

10 The object of the present invention is to improve the construction of back-band hooks and to provide a simple, strong, and durable one adapted to be easily applied to a back-band and readily adjusted thereon and capable 15 of securely holding a trace-chain and of preventing the same from accidentally slipping off of it.

A further object of the invention is to provide 20 a back-band hook which will be entirely on the exterior of the back-band in order to avoid any liability of chafing an animal.

The invention consists in the construction and novel combination and arrangement of parts, as hereinafter fully described, illustrated 25 in the accompanying drawing, and pointed out in the claims hereto appended.

The figure of the drawing is a perspective view of a back-band hook constructed in accordance with this invention and shown applied 30 to a portion of a back-band.

Referring to the drawing, 1 designates a back-band hook comprising a substantially rectangular frame 2 and an oblong loop 3, depending from the bottom of the frame and disposed in a plane at right angles to the same and forming the hook proper for the reception 35 of a trace-chain. The frame 2 comprises a transverse bottom portion and parallel sides, which terminate at their upper ends in eyes 4 and 5 for the reception of a pin, and the latter attaches the back-band hook to the back-band and also serves as a pintle for hinging the former to the latter to permit the back-band hook to swing outward. The pin, which 40 is provided at one end with a point, is inserted in the back-band, as illustrated in the accompanying drawing, and does not extend entirely through the same, so that the back-band hook is disposed entirely on the exterior 45 of the back-band to avoid any liability of chafing an animal.

The frame is provided at one of its eyes

with an arm 7, disposed substantially parallel with the adjacent side of it and adapted to be engaged by a substantially L-shaped 55 arm 8 of the adjacent end of the pin. The substantially L-shaped arm 8 of the pin serves as a handle and is connected with the pin by a bend or loop 9, which renders the arm 8 resilient, so that it may be readily sprung into 60 engagement with the straight arm 7 to provide a latch for locking the pin against longitudinal movement to prevent it from becoming accidentally withdrawn from the back-band. When it is desired to detach the back-band hook, the resilient arm 8 is adapted to be readily sprung out of engagement with the straight arm, which is normally arranged between the loop or bend 9 and the angle of the arm 8, as clearly shown in the drawing. 70

The oblong loop which forms the hook proper is composed of parallel inner and outer sides 10 and 11, connected at their lower ends by a bend, the outer side 11 being extended above the inner side and above the transverse 75 portion or bottom of the frame 2 and being provided at its top with an inwardly-extending arm 12. The oblong loop is practically closed at its top and bottom, and a link moving upward and downward on it cannot possibly become disengaged. 80

The loop and the frame may be cast in one piece or it may be constructed of a single piece of wire, as shown in the drawing, the wire being doubled on itself and bent to form the 85 oblong loop and then spread and bent to form the bottom and sides of the frame 2.

The advantages of the invention are as follows: The back-band hook is simple, strong, and durable and is adapted to retain a link 90 and prevent the same from being accidentally thrown out of engagement with it. It dispenses with a buckle and, while being readily adjustable on a back-band, is disposed entirely on the exterior of the same to avoid 95 chafing an animal. The attachment-pin, which enables the back-band hook to be readily applied to a back-band, forms a pintle and hinges the frame of the hook, and it is also locked against longitudinal movement, so that 100 it cannot become accidentally withdrawn from the back-band.

What I claim is—

1. A back-band hook comprising a frame

provided with opposite sides terminating at their upper ends in eyes, a hook proper depending from the frame, a removable pin passing through said eyes and adapted to secure 5 the frame detachably to a back-band, said pin being arranged at the top of the frame and forming a pintle to permit the device to swing outward, and a locking device detachably securing the pin in said eyes and consisting of 10 a pair of interlocking arms mounted respectively on the frame and the pin, substantially as described.

2. A back-band hook comprising a frame provided with opposite sides terminating at

their upper ends in eyes and provided at one 15 of the eyes with an arm, a hook proper depending from the frame, and a pin passing through said eyes and provided with a resilient arm engaging the arm of the frame and having an angle or bend receiving the same, 20 said pin forming a pintle and hinging the frame, substantially as and for the purpose described.

MARSHALL FRANKLIN DIAL.
